UNITED STATES PATENT OFFICE

94,121

DESIGN FOR A RUG

Edward A. Duval, New York, N. Y., assignor to
F. Schumacher & Co., New York, N. Y.

Application September 20, 1934, Serial No. 53,341

Term of patent 3½ years

To whom it may concern:

Be it known that I, Edward A. Duval, a citizen of the United States, and a resident of New York city, county and State of New York, have invented a new, original, and ornamental Design for a Rug, of which the following is a specification, reference being had to the accompanying drawing, forming part thereof.

In the drawing—

The figure is a plan view of the rug embodying the design.

I claim:

The ornamental design for a rug as shown.

EDWARD A. DUVAL.
